UNITED STATES PATENT OFFICE

146,435

DESIGN FOR A GLASS BOTTLE

Thomas Scott, Glasgow, Scotland

Application September 6, 1945, Serial No. 121,891

Term of patent 14 years

(Cl. D58—8)

To all whom it may concern:

Be it known that I, Thomas Scott, a subject of Great Britain and a resident of Glasgow, Scotland, Great Britain, have invented a new, original, and ornamental Design for a Glass Bottle, of which the following is a specification, reference being had to the accompanying drawing, forming part thereof.

Fig. 1 is a front elevational view of a bottle, showing my new design;

Fig. 2 is a sectional view taken on line II—II of Fig. 1, looking in the direction of the arrows;

Fig. 3 is a sectional view taken on line III—III of Fig. 1, looking in the direction of the arrows; and

Fig. 4 is a perspective view thereof.

I claim:

The ornamental design for a glass bottle, as shown.

THOMAS SCOTT.
